(57) **CLAIM**

We claim the ornamental design for an impulse therapy garment, as shown and described.

DESCRIPTION

FIG. 1 is an isometric view of an impulse therapy garment; FIG. 2 is a plan view of the outside of the embodiment shown in FIG. 1;

FIG. 3 is a side view of the embodiment shown in FIGS. 1-2;

FIG. 4 is another side view of the embodiment shown in FIGS. 1-3;

FIG. 5 is a side view that is opposite of the side view of the embodiment shown in FIG. 3;

FIG. 6 is a side view that is opposite of the side view of the embodiment shown in FIG. 4;

FIG. 7 is a plan view of the inside of the embodiment shown in FIGS. 1-6;

FIG. 8 is a perspective view thereof shown in use; and, FIG. 9 is another perspective view thereof.

The broken line showing of visible environmental structures is for illustrative purposes only and forms no part of the claimed design.
